UNITED STATES PATENT OFFICE.

WILLIAM S. TOTHILL, OF CHICAGO, ILLINOIS.

TEETER-LADDER AND THE LIKE.

1,113,384.

Specification of Letters Patent. Patented Oct. 13, 1914.

Application filed February 11, 1913. Serial No. 747,656.

To all whom it may concern:

Be it known that I, WILLIAM S. TOTHILL, a citizen of the United States, residing at Chicago, in the county of Cook and State of Illinois, have invented certain new and useful Improvements in Teeter-Ladders and the like, of which the following is a specification, reference being had to the accompanying drawings.

10 This invention relates to teeter ladders and the like. In the use of devices of this type heretofore there have been a great number of more or less serious accidents. As is readily understood, in the use of these devices, the users are raised alternately off the ground to the height of several feet. Whenever in the excitement of play one child has released his end of the ladder when the child on the other end of the ladder is still in raised position, there has been nothing to prevent the child from coming down to the ground at a dangerous speed, resulting in a shock and very often an accident of considerable seriousness.

25 It is the object of my invention to provide means, in connection with a device of this sort, by reason of which the child using the device may be guarded against being brought to the earth with a crash and shock 30 in the manner just described. The means by which I have accomplished this object are illustrated in the accompanying drawings and are hereinafter specifically described.

That which I believe to be new is set forth 35 in the claims.

In the drawings,—Figure 1 is a side view of the teeter ladder embodying my improvements; Fig. 2 is a side view of the same device, partly broken away, with the ladder in 40 turned position; Fig. 3 is a view, partly broken away, taken on line 3—3 of Fig. 1; Fig. 4 is a view, partly broken away, taken on line 4—4 of Fig. 1; Fig. 5 is a view similar to Fig. 4 but showing a modification 45 thereof; Fig. 6 is a modified form of device; Fig. 7 is a view, partly broken away, taken on line 7—7 of Fig. 6; and Fig. 8 is a view, partly broken away, taken on line 8—8 of Fig. 7.

50 Referring to Figs. 1 to 4,—20—21 indicate standards suitably mounted upon bases 22 and connected by cross-bars 23—24. 25—26 indicate the side-bars of a ladder pivotally mounted by means of a rod 27 between the 55 standards 20—21. The ends of the side-bars 25—26 of the ladder are of suitable

shape for being grasped for use in the ordinary manner, as will be readily understood. The side-bars 25—26 are provided at each side of the standards 20—21 with a cross-bar 28, to which two cross-bars 28 are connected by means of bolts or in any other suitable manner flat springs 29—30. As is shown in Figs. 1 and 4, when the ladder is in horizontal position the ends of the springs 29—30 are spaced away from the standards 20—21, but when the ladder is turned into an inclined position, as shown in Fig. 2, the springs are brought into contact with the standards whereby a further turning of the ladder from its horizontal position is yieldingly opposed. By reason of the construction just described, if the ladder is released by one of the users when the one at the other end of the ladder is at a height of several feet, the ladder is free to turn without restriction until one of the springs is brought into contact with the standard, after which the movement of the ladder is gradually eased and is finally stopped. These 80 cushioning devices serve to remove the shock and the strain which would otherwise be experienced upon such a fall and also serve as a stop to limit the movement of the end of the ladder downward whereby the body of 85 the user is kept out of contact with the ground.

Referring to Fig. 5, in which corresponding parts are indicated by the same reference characters, but with the addition of the exponent "a," 31 indicates a heavy board which takes the place of the ladder used in the construction heretofore described. As shown in Fig. 1, the standards 20—21 are provided with a plurality of registering 90 openings through which the pivot rod 27 can be inserted for holding the ladder 25 at the desired height. It is designed that the standards 20^a—21^a be provided with additional openings for the insertion of the 95 pivot rod 27^a whereby the board 31 may be held at the desired height somewhat nearer the base than is desired for use of the ladder 25.

Referring now to Figs. 6, 7 and 8, which 105 show a modified form of my device, 32 indicates a standard the lower end of which is supported in the ground or in any other suitable manner, in the construction shown said standard being in the form of a cylindrical pipe. 33 indicates a head slidably mounted upon the standard 32 being ro-

tatably supported thereon by means of a sleeve 34 which is held in the desired position on the standard by means of a pin 35 which is adapted to be inserted through any 5 one of a number of openings through the standard 32. The head 33 is also provided with registering openings 36 on its opposite sides through which the pin 35 is adapted to be inserted if desired whereby the head 10 is held fixed at the desired elevation. As best shown in Fig. 7, the head 33 is provided with two laterally-extending pins 37-38 upon which is pivotally mounted a ladder comprising side-bars 39-40. As shown in 15 Fig. 7, the head 33 is provided at each side with a laterally-extending arm 41, upon the outer ends of which arms are secured by means of clips 42 or in any other appropriate manner flat springs 43-44. It will be 20 noted that the springs 43-44 serve the same purpose in connection with the ladder 39-40 as do the springs in the construction first described in connection with the ladder, serving to cushion the movement of the ladder. 25 In the modified form of construction just described, however, the ladder is capable of being turned about the standard as a pivot, the springs serving as described in whatever position the ladder is turned. 30 That which I claim as my invention, and desire to secure by Letters Patent, is,—
1. In a device of the character described, the combination of a support, a teeter device pivotally mounted thereon, and a plurality 35 of flat springs mounted upon the said teeter device on opposite sides of said support, said springs being adapted at a predetermined point in the turning of said teeter device to contact said support and yieldingly oppose 40 the turning of said teeter device.
2. In a device of the character described, the combination of a support comprising two standards spaced apart, a teeter device pivotally mounted upon said support, and flat 45 springs mounted on said teeter device two at either side thereof arranged on opposite sides of said standards, said springs being adapted at a predetermined point in the turning of said teeter device upon said

standards to be brought into contact with 50 the standards whereby the turning of said teeter device is limited and cushioned.

3. In a device of the type described, the combination of a support, a teeter device pivotally mounted thereon, and a spring 55 carried by one of said members in such position that it is out of contact with the other member when the teeter device stands in horizontal position, but that it contacts said other member when the teeter device has 60 moved to a certain predetermined inclined position.

4. In a device of the type described, the combination of a support, a teeter device pivotally mounted thereon, and springs 65 mounted on said teeter device on opposite sides of said support, said springs being spaced away from said support when said teeter device is in horizontal position, but being adapted to contact said support when 70 said teeter device has moved to a certain predetermined inclined position.

5. In a device of the type described, the combination of a support, a teeter device pivotally mounted thereon, and flat springs 75 mounted on the teeter device on opposite sides of said support and extending toward the support, said springs being adapted at certain predetermined points respectively in the turning of said teeter device to contact 80 said support and yieldingly oppose the further turning of said teeter device.

6. In a device of the type described, the combination of a support, a teeter device pivotally mounted thereon, and flat springs 85 mounted on the teeter device on opposite sides of said support and extending toward the support, said springs being curved at their inner ends adjacent to said support, said springs being adapted at certain pre- 90 determined points respectively in the turning of said teeter device to contact said support and yieldingly oppose the further turning of said teeter device.

WILLIAM S. TOTHILL.
